SHOWER CURTAIN HOOK

Wesley Soderstrom, Rockford, Ill., assignor to Western Newell Mfg. Co., Freeport, Ill., a corporation of Illinois

Application December 7, 1950, Serial No. 13,308

Term of patent 14 years

(Cl. D4—3)

To all whom it may concern:

Be it known that I, Wesley Soderstrom, a citizen of the United States, residing at Rockford, in the county of Winnebago and State of Illinois, have invented a new, original, and ornamental Design for Shower Curtain Hook, of which the following is a specification, reference being had to the accompanying drawings, forming part thereof.

In the drawings:

Fig. 1 is a side view of a shower curtain hook embodying my new design, the opposite side being a counterpart in design to the side shown, and

Fig. 2 is a rear view of Fig. 1.

I claim:

The ornamental design for a shower curtain hook, substantially as shown and described.

WESLEY SODERSTROM.
